ADHESIVE TAPE SEVERING CLIP

George W. Riddle, Jr., Chillicothe, Mo.

Application February 1, 1935, Serial No. 4,539

1 Claim. (Cl. 206—59)

This invention relates to a unique cutter or severing clip which is particularly designed for use in connection with conventional spools such as are used as present day holders for so-called adhesive tape.

5 It is a matter of common knowledge that all sorts of make shift devices are employed for cutting off a piece of adhesive tape when it is desired to use it. Sometimes it is done with a knife, then again with a pair of scissors and some spools are provided with integral cutting elements.

10 In accordance with my conception I have evolved and produced a simple and economical bodily detachable clip which may be made and sold separately from the spool or utilized as an accessory in conjunction with the spool at the time of the sale.

15 In reducing the invention to actual practice, I have found it expedient and practicable to employ a simple plate against which the thumb is placed and held, said plate having confining or retaining elements to fit between the edges of the tape and the disk-like heads of the spool and being further provided with a cutting blade so 20 that it is possible to easily tear off or shear the desired length of tape.

25 My primary aim is to provide a unique cutter which is in keeping with the requisites of simplicity and practicability, whereby to promote efficiency and to provide for appreciated economy.

30 Other features and advantages will become more readily apparent from the following description and drawing.

In the drawing:

35 Figure 1 is an elevational view showing a conventional spool and adhesive tape and illustrating the manner in which the severing unit or device is employed.

40 Figure 2 is a sectional view taken approximately on the plane of the line 2—2 of Figure 1.

45 Figure 3 is a perspective view of the cutter per se.

Figure 4 is a longitudinal sectional view through the cutter as a unit.

50 In the drawing, the spool is denoted as a unit by the numeral 6 and this includes the conventional hub having a pair of disk-like heads 8 between which the adhesive tape 7 is wound in the customary manner. The cutting clip or device is differentiated by the numeral 8 and this 55 comprises a simple clip including a body or plate 9 of appropriate dimension to fit between the disks 8. At one end, the plate is provided with a cutting blade 10 of appropriate dimension. In addition, the plate is equipped with confining or

retaining elements 11. Specifically, I simply take a plate of metal and bend the free edges down to form interconnected flanges. The two spaced parallel flanges 11 constitute the retaining elements, and these are adapted to be slipped down between the edge portions of the rolled tape and the disk-like heads on the spool. The remaining flange 10 is then located in a proper position to serve as a shearing or cutting knife. This also permits the plate to occupy a convenient inclined position so that the cutting blade 10 can be forced down with the thumb under sufficient pressure to facilitate tearing or shearing of the end of the tape.

55 From this it follows that the flanges 11 will remain between the edges of the rolled tape and the spool head and retain the cutting device in position, notwithstanding it may be necessary to rock the cutting device on the perimeter of the rolled tape, as a fulcrum, in pressing the edge of the blade 10 against the tape precedent to shearing off a portion of the tape.

60 It is thought that persons skilled in the art to which the invention relates will be able to obtain a clear understanding of the invention after considering the description in connection with the drawing. Therefore, a more lengthy description is regarded as unnecessary.

65 Minor changes in shape, size and rearrangement of details coming within the field of invention claimed may be resorted to in actual practice, if desired.

70 What I claim as new is:

The herein described means for holding and dispensing tape comprising a spool having a hub 35 and spaced heads at the ends of the hub, said hub being adapted to have coiled thereon a length of tape with the edges of the tape in spaced relation to the inner sides of the heads, and a cutting device disposed between the heads of the spool 40 and against the outermost convolution of the coiled or rolled tape, said cutting device consisting essentially of a flat rectangular plate having a depending rectangular-shaped cutting flange 45 at one end and disposed at right angles to said plate and also having on its side edges depending flanges of even width throughout extending from said cutting flange to the remote end of the plate, said flanges resting between the edges of the coiled or rolled tape and the spool heads whereby the cutting device is held in working position notwithstanding the rocking thereof on the periphery of the rolled or coiled tape incidental to the use of the cutting device.
